(57) **CLAIM**

The ornamental design of the combined socket wrench and socket holder, as shown and described.

DESCRIPTION

FIG. 1 is a front elevational view of the combined socket wrench and socket holder of my new design;

FIG. 2 is a rear elevational view thereof;

FIG. 3 is a side elevational view of the right side thereof;

FIG. 4 is a side elevational view of the left side thereof;

FIG. 5 is a top plan view thereof;

FIG. 6 is a bottom plan view thereof;

FIG. 7 is a front elevational view of the socket holder of FIG. 1;

FIG. 8 is a side elevational view of FIG. 7, the opposite side elevational view being a mirror image thereof; and,

FIG. 9 is a top plan view of FIG. 7, the bottom plan view being a mirror image thereof.

The socket holder of the combined socket wrench and socket holder is shown separately for ease of illustration.
